FLEXIBLE SUPPORT FOR DENTAL AND SURGICAL INSTRUMENTS

David T. Adler, Plainview, N.Y.
(5 Lenox Ave., Farmingdale, N.Y. 11735)

Filed Apr. 5, 1973, Ser. No. 348,184

Term of patent 14 years

Int. Cl. D24—01

U.S. CL. D24—1 B

FIG. 1 is a front elevation view of a flexible support for dental and surgical instruments showing my new design;

FIG. 2 is a top or plan view thereof; and

FIG. 3 is a left side elevation with portions broken away for ease of illustration.

I claim:

The ornamental design for a flexible support for dental and surgical instruments, as shown and described.
